(57) **CLAIM**

The ornamental design for a ground fault interrupter receptacle with dual indicator lights, as shown and described.

DESCRIPTION

FIG. 1 is a front view of a ground fault circuit interrupter receptacle with dual indicator lights, showing our new design;

FIG. 2 is a side perspective view thereof;

FIG. 3 is an opposing side perspective view thereof;

FIG. 4 is a front view thereof;

FIG. 5 is a side view thereof;

FIG. 6 is an opposing side view thereof;

FIG. 7 is another front view of a ground fault circuit interrupter receptacle with dual indicator lights, showing our new design;

FIG. 8 is a side perspective view thereof;

FIG. 9 is an opposing side perspective view thereof;

FIG. 10 is a front view thereof;

FIG. 11 is a side view thereof; and,

FIG. 12 is an opposing side view thereof.

In the drawings, the broken lines are for the purpose of illustrating environment only and form no part of the claimed design.
